B. RANZAN

AUTOMATIC EXPLOSIVE MECHANISM

Filed Sept. 19, 1927

UNITED STATES PATENT OFFICE.

BORIS RANZAN, OF NEW YORK, N. Y.

AUTOMATIC EXPLOSIVE MECHANISM.

Application filed September 19, 1927. Serial No. 220,518.

This invention relates to a device for exploding an explosive charge and has for one of its objects the provision of trigger mechanism adapted to be employed on the rail 5 of a railway for exploding a charge when a train passes thereover.

Another object of my invention is the provision of a clock operated trigger mechanism adapted to explode a charge at a predetermined time.

A further object of my invention is the provision of safety mechanism on an explosive device for rendering the actuation thereof impossible until after manipulation 15 of external adjusting mechanism.

A still further object of my invention is the provision of means for exploding a charge including trigger mechanism adapted to be employed on a railway rail, and an 20 automatically operated safety device adapted to engage said exploding mechanism for rendering the same operative for a predetermined length of time after the first train passes over the trigger mechanism for giving 25 a signal in the event that two trains pass over the same portion of the rail in an undesirably close sequence.

Other objects and advantages will appear hereinafter, the novel features and combinations being more clearly set forth in the appended claims.

In the drawing:

Fig. 1 is a side elevational view partly in section, of a rail and rail bed equipped 35 with my invention.

Fig. 2 is a longitudinal sectional view of my invention.

Fig. 3 is a transverse sectional view, taken on the line 3—3 of Fig. 2.

Fig. 4 is a longitudinal sectional view of a 40 modified form of my invention.

In the accompanying drawing, 10 designates a railway bed having ties 11 mounted thereon and rail ends 12 mounted on the ties 45 in the customary manner. The extremities of the rail ends are spaced apart providing sufficient space for expansion and for a further purpose, hereinafter more clearly set forth. As shown in Fig. 1, a rectangular 50 casing 13 is disposed below the surface of the rail bed and is provided with a slidably guided rod 14, disposed through an aperture in the casing 13 at one extremity and extending through the space between the rail

ends 12 to a position above the surface of 55 the rails at the other end.

It will be seen in Fig. 2 that the casing 13 comprises a left and right hand compartment 15 and 16, respectively, separated by a partition 17. The right hand compartment 60 16 is adapted to receive a container 18 filled with an explosive substance. The casing 13 is open at its right hand extremity and is adapted to be closed by the end 19 of the container 18. A tubular member 20 65 is made integral with the left hand end 21 of the container, 20 communicating at one extremity with an aperture 22 in the end 21 and being provided with an inwardly disposed flange 23 on the other end. The tubular member 20 is adapted to hold a cartridge 24 in position to be exploded.

A guide member 25 is mounted on the partition 17 of the left hand chamber 15 and extends into the latter. A firing pin 26 is 75 disposed through an aperture in the partition 17 and extends at its pointed end into the tubular member 20. The firing pin 26 is slidably mounted in the aperture of the partition 17 and is provided with a spring 27 80 disposed within the tubular member 20 between the partition 17 and a flange 28 on the pin 26. The left hand extremity of the firing pin 26 is provided with a notched extension 29 which is adapted to engage with 85 the notched extremity 30 of a lever 31 pivotally mounted on a pin 32 secured at its ends to the sides of the casing 13. A spring 33 is attached at one extremity to a bracket 34 mounted on the top wall of casing 13 and 90 is attached at its other extremity to the lever 31. The spring 33 is adapted to urge the notched extremity 30 of the lever 31 downwardly into engagement with the notched extension 29 of the firing pin 26.

The lower end of the rod 14 extends through the top wall of the casing 13 and terminates above the lever 31. The lever 31 is provided with guide rods 36 about which the spring 37 is slidably mounted. The 100 lower extremity of the rod 14 is provided with a plunger 38 which is adapted to rest upon the spring 37. A shaft 39 is rotatively mounted in the side of the casing and is positioned so that its circumference is in contact 105 with the upper edge of the notched extremity 30 of the lever 31. The shaft 39 is provided with a notch 40 into which the

extremity of the lever 31 may pass when the shaft 39 is in the position shown in Fig. 2, for releasing the notched extension 29 of the firing pin 26. It should be understood that the shaft 39 may be rotated to a position out of registration with the notch 40 so as to prevent the disengagement of the extension 29. The handle 30 of the shaft 39 is externally positioned and is adapted to rotate said shaft.

When the shaft 39 is positioned as viewed in Fig. 2 the passage of a train wheel over the rail ends 12 will cause the rod 14 to be urged downwardly and the lever 31 operatively connected with the extremity of the rod 14 to be rotated in an anticlockwise direction releasing the firing pin 26 and permitting the same to be projected against the end of the cartridge 24, the explosion of which will explode the charge in the container 18. It should be understood that when the shaft 39 has been rotated through 180° from the position illustrated, the lever 31 is restrained from rotation and that all movement of the rod 14 is absorbed by the compression spring 37.

As illustrated in Figs. 2 and 3, the trigger mechanism may be actuated at a predetermined time by the clock 41. In order to accomplish this result the left hand end of the lever 31 is provided with an arm 42 which is mounted on the lever 31 by the bolt 43 and nut 44. The turn key 45 of the alarm clock is that key which is employed in winding the alarm spring, not shown in the drawing, which, as in ordinary alarm clock construction, rotates when the alarm goes off. When the key 45 commences to rotate at the desired time, it engages the arm 42 and urges the left hand end of the lever 31 in an anti-clockwise direction causing the firing pin 26 to be released. It should be understood that when it is desired to use the device for signaling the charge of explosive may be omitted and only a blank cartridge employed.

In the modified form of my invention illustrated in Fig. 4, the mechanism above described is employed in connection, with means for automatically positioning the shaft 39. With this form of my invention it is desired to produce a device that will give a signal at any time when two trains pass over the same portion of the track in undesirably close sequence to inform the engineer of the second train that the first train is not far ahead.

As shown in Fig. 4, the shaft 39 is provided with a worm gear 46 having a plurality of spaced-apart apertures 47 therein by means of which the gear 46 is adjustably attached to the shaft 39. Brackets 48 secured to the shaft 39 are provided with apertures which register with the apertures in the gear 46 and are adapted to receive bolts 49.

An electric motor 50 is mounted on a base

member 51 secured to the wall of the casing 13 and is provided with a worm 52 meshed with the teeth of the worm gear 46. The motor 50 is adapted to rotate the gear 46 in an anti-clockwise direction.

An arm 53 comprising a downwardly directed finger 54 is rigidly attached to the rod 14 and is adapted to move vertically therewith when the upper end of the rod 14 is engaged by a wheel of a train. A switch comprising an insulating base member 55 mounted on the wall of the casing 13 and two resilient contact elements 56 and 57 are disposed directly below the finger 54. The contact element 57 is longer than the contact element 56 and is disposed upwardly at an inclination thereto and normally engages the same. The contact element 57 is disposed in the path of a pin 58 mounted on the worm gear 46 which is adapted to urge the contact element downwardly out of contact with the element 56 when the gear 46 reaches a predetermined position. The contact element 56 of the switch is directly electrically connected with one terminal of the motor 50 and the other terminal of the motor is electrically connected with one terminal of a source of power illustrated at 59, the other terminal of the source of power 59 being electrically connected with the contact element 57.

Starting with the mechanism positioned as illustrated in Fig. 4, when the rod 14 is moved downwardly by the wheels of the first train the lever 31 is restrained from movement by the shaft 39. This first downward movement of the rod 14, thus, does not cause actuation of the firing mechanism but, however, when the arm 53 and finger 54 are urged downwardly together with the rod 14, the finger 54 engages the contact element 56 and causes the latter to engage contact member 57. An electrical circuit is thus completed through the motor 50 which is excited and produces rotation of the worm gear 46. When rotation of the gear 46 commences the pin 58 passes out of engagement with the contact member 57 and permits the latter to assume its normal position in contact with the contact element 56, thus causing the electrical circuit through the motor to be completed after the rod 14 has been returned to its extended position by the spring 37. The worm gear continues to be rotated by the motor 50 until the pin 58 thereof is returned to its starting position and reengages the contact element 57 of the switch.

It should be understood that when the first train passes, the firing mechanism is rendered inoperative by the shaft 39 and that the passage of the first train causes the shaft 39 to rotate as above described bringing the notch 40 of the shaft into registration with the right hand end of the lever 31. If a second train passes the rail ends 12

while the notch is in registration with the end portion of the lever 31 the firing pin will be released as above described but if a second train does not pass over the rail ends 5 12 within the predetermined period during which the notch 40 is in registration with the lever 31 then the passage of the second train over the end of the rod 14 will merely result in the recurrence of the cycle de- 10 scribed.

It should be understood that the timing of the mechanism may be varied by changing the position of the pin 58 of the worm gear 46 relative to the notch 40 of the shaft 39.

Having thus fully shown and described my invention what I claim as new and wish to protect by Letters Patent of the United States is:

1. In a device of the class described a bomb comprising a casing adapted to be disposed below the rail bed of a railway, a firing pin slidably mounted in said casing, a trigger mechanism adapted to retain said firing pin in a retracted position, a spring mounted in said casing for urging said firing pin, and actuating mechanism for said trigger mechanism comprising an alarm clock adapted to actuate the same at a predetermined time for releasing said trigger mechanism to dis- 30 charge said bomb.

2. In a device of the class described, the combination with a pair of adjacent rail ends positioned in spaced relation, of a rod slidably mounted between said rail ends and ex- 35 tending thereabove at one end, a casing disposed below said rail ends in the bed of said rails, having an aperture in the upper wall thereof for slidably accommodating the lower portion of said rod, a partition in said casing dividing the same into right and left compartments, a bomb disposed in said right compartment comprising an explosive filled container, a tubular member mounted on one wall of said container comprising a flanged extremity, a cartridge mounted in said flanged extremity and a firing pin slidably mounted in said tubular member comprising a pointed extremity.

3. In a device of the class described, a signal device comprising a casing adapted to be disposed below the surface of a rail bed, a firing pin slidably mounted in said casing, a cartridge mounted in said casing adapted to be engaged by said firing pin, 50 an extension on said firing pin comprising a notched end portion, a lever pivotally mounted in said casing comprising a notched extremity adapted to engage the notched extremity of said firing pin for retaining the latter in a retracted position, a shaft rotatively mounted in said casing having a notched portion in registration with said lever, a worm gear adjustably mounted on said shaft, an electric motor mounted in said casing, a worm on said motor meshed with

said worm gear, a switch mounted in said casing for controlling the excitation of said motor, a vertically disposed rod slidably mounted in an aperture in said casing in registration with said lever, a spring dis- 70 posed between the end of said rod and said lever adapted to engage said cartridge for firing the same, an extension on the other end of said firing pin disposed in the left compartment of said casing comprising a 75 notched extremity, a lever comprising a notched extremity pivotally mounted in said container adapted to engage the notched ex- 80 tension of said firing pin for retaining the latter in a retracted position, a spring mounted on said lever in registration with said rod adapted to be urged downwardly by said rod for rotating said lever to re- 85 lease said firing pin, and a spring mounted in said tubular member for urging said fir- 90 ing pin against said cartridge when said firing pin is released to explode said bomb.

4. In a device of the class described, a signal device comprising a casing adapted to be disposed below the surface of a rail bed, a firing pin slidably mounted in said casing, a cartridge mounted in said casing adapted to be engaged by said firing pin, an extension on said firing pin comprising a notched end portion, a lever pivotally mounted in said casing comprising a notched extremity adapted to engage the notched extremity of said firing pin for retaining the same in a retracted position, a shaft rotatively mounted in said casing having a 95 notched portion in registration with said lever, a worm gear adjustably mounted on said shaft, an electric motor mounted in said casing, a worm on said motor meshed with said worm gear, a switch mounted in said casing for controlling the excitation of said motor, a vertically disposed rod slidably mounted in an aperture in said casing in registration with said lever, a spring dis- 100 posed between the end of said rod and said lever adapted to engage said cartridge for firing the same, an extension on the other end of said firing pin disposed in the left compartment of the said casing comprising a 105 notched extremity, a lever comprising a 110 notched extremity pivotally mounted in said container adapted to engage the notched ex- 115 tension of said firing pin for retaining the latter in a retracted position, a spring mounted on said lever in registration with said rod adapted to be urged downwardly by said rod for rotating said lever to release said firing pin, a spring mounted in said tubular member for urging said firing pin against said cartridge when said firing pin is released to explode said bomb, and a 120 safety mechanism for restraining rotation of said lever comprising a shaft rotatively mounted in said casing having a notched portion therein adapted to be positioned in 125 130

and out of registration with said lever, a pin on said worm gear adapted to engage one contact element of said switch for interrupting the circuit therethrough when 5 said gear is in a predetermined position and an arm on said vertical rod comprising a finger adapted to engage said switch for closing an electric circuit therethrough when said rod is depressed for rotating said gear 10 to disengage said pin from said contact member, said contact member being adapted to close the circuit through said switch when disengaged from said pin for effecting rotation of said shaft to position the notch 15 thereof in registration with said lever to render said lever free to be rotated when said rod is again depressed to release said firing pin.

5. In a signal device of the class described, a casing, a firing pin slidably

mounted in said casing, means for retaining said firing pin in retracted position comprising a pivotally mounted lever operatively connected at one end with said firing pin, a shaft having a notch therein mounted in 25 said casing adapted when in one position to retain engagement between said lever and said firing pin, driving means for rotating said shaft to position said notch in registration with said lever to permit disengagement of said firing pin therefrom and a trigger operatively connected with said lever adapted upon first depression to actuate said driving means and upon second depression within a predetermined period thereafter to 30 actuate said lever for releasing said firing pin.

In testimony whereof I have affixed my signature.

BORIS RANZAN.
